(57) **CLAIM**

The ornamental design for a patient dialysis garment, as shown and described.

DESCRIPTION

FIG. 1 is a perspective view of a patient dialysis garment showing my new design;

FIG. 2 is a front elevational view thereof;

FIG. 3 is a rear elevational view thereof; and,

FIG. 4 is a front elevational showing the top flap of the garment and the sleeves adapted to a closed position.

The broken lines shown in the drawings are for illustrative purposes only and form no part of the claimed design.
